(57) **CLAIM**

The ornamental design for an exercise band, as shown and described.

DESCRIPTION

FIG. 1 is an isometric view of the exercise band according to the present invention.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a perspective view of the exercise band showing my new design while in use thereof; and,

FIG. 9 is another perspective view of the exercise band showing my new design while in use thereof.

The broken dash lines in the figures depict portions of the exercise band that form no part of the claimed design. Neither the portions of the exercise band shown in broken dash line nor the broken dash lines themselves form any part of the claimed invention.

The broken dash-dot lines in FIGS. 1, 2, 3, 4, 5, 8, and 9 are used to show a symbolic break in the length of the exercise band. Neither the lines themselves nor the appearance of any portion of the article between the break lines forms any part of the claimed design.

The broken dash-dot-dot lines in FIGS. 8 and 9 are for illustrative purposes only and represent non-claimed environmental subject matter. Neither the environmental subject matter shown in broken dash-dot-dot lines nor the broken dash-dot-dot lines themselves form any part of the claimed invention.
